US00D733886S

(12) **United States Design Patent**
Casement et al.

(10) **Patent No.:** **US D733,886 S**
(45) **Date of Patent:** **** Jul. 7, 2015**

(54) **PROVISIONAL DENTAL IMPLANT**

(71) Applicant: **Provisional Implant Technology LLC**,
Denver, CO (US)

(72) Inventors: **Russell Casement**, Parker, CO (US);
Kelley Casement, Denver, CO (US);
Ricardo Gapski, Parana (BR)

(73) Assignee: **Provisional Implant Technology, LLC**,
Denver, CO (US)

(**) Term: **14 Years**

(21) Appl. No.: **29/471,531**

(22) Filed: **Nov. 1, 2013**

(51) LOC (10) Cl. **24-02**

(52) U.S. Cl.

USPC **D24/156**
